F. F. AMBROSE

SCREW PUMP

Filed Jan. 14, 1925

UNITED STATES PATENT OFFICE.

FRANK F. AMBROSE, OF LOS ANGELES, CALIFORNIA.

SCREW PUMP.

Application filed January 14, 1925. Serial No. 2,300.

My invention relates to that class of pumps described in United States Letters Patent No. 529,837 of date Nov. 27, 1894, in which there are employed two pairs of intermeshing threads, right and left and left and right respectively. In pumps of that class there has been heretofore no means of adjustment to adapt the pump for pumping liquids of different viscosity without the loss of efficiency and power. It is the object of my improvement to so construct a pump of that class which can readily be changed to pump a liquid of a heavier viscosity than the liquid for which the pump is primarily designed to pump.

In the drawings forming a part of this application Fig. 1 is a side elevation with parts broken away of my improved pump. Fig. 2 is a side elevation of certain of the parts shown in Fig. 1 from which parts have been removed for illustration. Fig. 3 is a section on the line 3—3 of Fig. 1 of the pumping chamber and the inlet chamber, the base being omitted and the supports broken away. Fig. 3^a is a longitudinal vertical section on the line 3^a—3^a of Fig. 3 with the central shaft bearing shown in full lines. Fig. 4 is a top plan of a slight modification of the pump shown in Fig. 1 with parts broken away.

In the drawings 5 is the base block which is secured to the floor 6 by bolts 7. 8—9—10 are pedestals which are mounted upon 5 being secured thereto by bolts, not shown. 35 These pedestals extend to the center of shafts 11 and 12 and support the bearings and bushings for said shafts. The tops of pedestals 9 and 10 are connected by gear case 13 through which shafts 11 and 12 pass. 40 Shafts 11 and 12 are provided with intermeshing right and left hand screw threads 14 and 15 like the threads described in said Patent 529,837. These threads work in casing 17 which is mounted upon base 5. Shafts 45 11 and 12 are connected by herring-bone gears 16 which revolve in casing 13. Shaft 11 terminates at pedestal 10 and shaft 12 extends to and is driven by motor 18 mounted on base 5. Case 13 and pedestals 9 and 10 50 are provided with a cap 21 which is secured thereto by bolts 22. Pedestal 8 has a cap 23 which is secured thereto by bolts 24. Casing

17 is provided with a top 26 which is secured thereto by bolts 27. Casing 17 and top 26 form the pumping chamber 28 in which 55 threads 14 and 15 work. Channels 29 open into chamber 28 at the outer ends thereof and connect the inlet chamber 30 with chamber 28. Chambers 28 and 30 have ports 28^a and 30^b opening thereinto on both sides 60 of the casings forming said chambers, thereby facilitating the installation of the pump and enabling the pump to be connected to the source of supply by two lines of pipes and to enable the discharge of the liquid pumped 65 by two lines of pipes. That portion of casing 17 between chambers 28 and 30 I term web 36. In the drawings I have shown the ports on one side connected by pipes 31 and 32 to a source of supply and a place of discharge respectively. The ports on the other side are covered by plates 34. Shafts 11 and 12 are provided with bearings 19 which are split on the central horizontal plane which passes through the shafts. By splitting the 70 bearings and the gear case and pump chamber casing on the plane which passes horizontally through the centers of shafts 11 and 12 if it is desired to use the pump to 75 pump liquid of a heavier viscosity than it was originally designed for I can shim up the parts so as to provide a larger pumping 80 chamber which enables me to pump heavier liquid. I provide shafts 11 and 12 between threads 14 and 15 with bearings 20 which are 85 supported by casing 17 and cap 27. These bearings are held from longitudinal movement by lag bolts 25. In Fig. 4 I have shown a slight modification of the pump shown in 90 Fig. 1 which consists in extending shaft 12 at the end opposite motor 18 and providing it with independent driving means shown as motor 35.

Having described my invention I claim—

1. In a screw pump of the character described, a pump chamber casing divided longitudinally and horizontally on the plane that passes through the centers of the screws, said casing having in the upper portion a pumping chamber and in the lower portion an inlet chamber, said chambers being separated by a web and being connected at the outer ends by ports, each chamber having a port that opens through the casing and in

that portion of the casing below the division line between the parts thereof.

2. In a pump of the character described, a pump chamber casing having formed in the upper portion thereof a pumping chamber, said casing being longitudinally and horizontally split on the center line of the pump-

ing chamber and having ports therein below the line of the split.

In witness that I claim the foregoing I 10 have hereunto subscribed my name this 8th day of January, 1925.

FRANK F. AMBROSE.
